United States Patent Office.

JESSE S. BUTTERFIELD AND JOSEPH A. READ, OF PHILADELPHIA,
PENNSYLVANIA.

Letters Patent No. 71,974, dated December 10, 1867.

IMPROVED SAD-IRON.

The Schedule referred to in these Letters Patent and making part of the same.

TO ALL WHOM IT MAY CONCERN:

Be it known that we, JESSE S. BUTTERFIELD and JOSEPH A. READ, of the city of Philadelphia, in the State of Pennsylvania, have invented a new and useful Improvement in the Sad-Iron; and we do hereby declare that the following is a full, clear, and exact description of the construction and operation of the same, reference being had to the accompanying drawings, making a part of this specification, in which—

Figure 1 is a side elevation of the said improved sad-iron.

Figure 2, an end elevation of the base, and a sectional view of the handle of the same detached.

Figure 3, a plan view of the central portion of the upper side of the base; and

Figure 4, a plan view of the under side of the handle—

Like letters of reference indicating the same parts when in the different figures.

Our improvement relates to those sad-irons which have detachable handles; and the nature of our invention consists in the peculiar manner, hereinafter described and specified, of constructing and applying the detachable handle to the base of the sad-iron, whereby a single handle can be attached to, and detached from, any one of a series of bases, as occasion may require, with greater facility and security than heretofore.

Referring to the drawings, A B are the base, and C D the detachable handle of the same. On the upper side of the base A B, and near its centre of gravity, a tapering circular projection, a', is cast, or otherwise fixed, which has two horizontally projecting sectors or portions a'' a'', separated by two lateral spaces b' b', and sloped or inclined in opposite directions on their under sides, like the under side of the square screw-thread of a vertical bolt or nut. The upper end of a' has a deep cavity in its centre, and the circular boundary of the latter is notched and sloped, so as to form two oppositely inclined planes, a''' a'''. The handle C D has two feet c' c', connected together above by a curved plate, d', which is broad enough to defend one's hand from the heat of the base A B while using the sad-iron legitimately. On the centre of the under side of d' there is a conical stud or steadyng-pin, d'', which will loosely fit in the cavity in the upper end of a'; and at the opposite sides of its base there are two shoulders or sectors d''' d''', which will come in contact with the respective notches of the two inclined planes of the upper end of a', when the handle C D is to be detached from the base A B, and thus stop its movement at the proper place for detaching. The feet c' c' of the handle C D have each a flat, inward-projecting portion, c'' c'', which will, respectively, pass down through the spaces b' b', between the ends of the planes a'' a'' of the projection a', in applying the handle to the base, and will also slide under the said planes a'' on turning the handle around toward the right hand. In fig. 2 the handle is shown as in the transverse position required to enter the parts c'' c'' and d'', as above described. Through a hole in the forward foot-end of the handle a drop-pin, e, is placed, the lower end of which will drop into a corresponding hole (see dotted line v) in the base A B, when the handle is turned around into the position shown in fig. 1.

Operation.

Several of the bases A B (without handles) being placed on a heater, any one of them may be taken up and used by placing the handle C D transversely over the middle of the base A B, entering the steadyng-pin d'' into the cavity in a', and the projecting end c'' c'' of the feet c' c' into the respective spaces b' b', and then by turning the handle around to the right, so as to pass the said projections c'' c'' under the projections a'' a'', and continuing the turning of the handle around to the right, the pin e drops into the hole made for it in the forward part of A B, thus stopping and securely attaching the handle in a moment. In detaching the handle on returning the base to the heater, it is only necessary to raise the drop-pin e by the thumb and finger of the hand which grasps the handle, and then to turn the handle back to its first position across the base, the sectors d''' d''' catching against the notches which are between the two planes a''' a''', and thus stopping the rotary motion of the handle when the latter has reached the proper position to be lifted up or withdrawn. This is a very easily operated, effective, and durable device for the purpose.

Having thus fully described our improvement in the sad-iron, what we claim as new therein of our invention, and desire to secure by Letters Patent, is confined to the following, viz:

1. We claim the steadyng-pin d'', in combination with the sectors d''' d''' on the guard-plate d', the said

parts being constructed and arranged to operate in connection with the planes $a''' a'''$ on the projection a' , substantially as and for the purpose described.

2. We claim the projection a' on the base A B, with its two opposite sectors or inclined planes, $a'' a''$, constructed and arranged to receive and hold down the inward ends $c'' c''$ of the feet of the handle C D, substantially as described and set forth.

3. We claim the projecting ends $c'' c''$ of the handle C D, constructed and arranged to operate in combination with the spaces $b' b'$ and planes $a'' a''$, substantially as and for the purpose described.

J. S. BUTTERFIELD,
JOSEPH A. READ.
